DESIGN FOR A ROCKING CHAIR

Edward Bird, London, England

Application June 5, 1946, Serial No. 130,434
In Great Britain January 28, 1946

Term of patent 14 years

(Cl. D15—6)

To all whom it may concern:

Be it known that I, Edward Bird, a subject of the King of Great Britain, residing at Casita, Uffington Road, London N. W. 10, England, have invented a new, original, and ornamental Design for a Rocking Chair, of which the following is a specification, reference being had to the accompanying drawing, forming part thereof.

Fig. 1 is a front perspective view of a rocking chair, showing my new design; and

Fig. 2 is a rear perspective view.

I claim:

The ornamental design for a rocking chair, as shown.

EDWARD BIRD.
